(No Model.)

J. CLAPP.
AUTOMATIC VALVE.

No. 440,100.

Patented Nov. 4, 1890.

UNITED STATES PATENT OFFICE.

JOSEPH CLAPP, OF EVANSTON, ASSIGNOR TO THE CLAPP AUTOMATIC FIRE EXTINGUISHER COMPANY, OF CHICAGO, ILLINOIS.

AUTOMATIC VALVE.

SPECIFICATION forming part of Letters Patent No. 440,100, dated November 4, 1890.

Application filed October 26, 1889. Renewed October 2, 1890. Serial No. 366,829. (No model.)

To all whom it may concern:

Be it known that I, JOSEPH CLAPP, of Evanston, in the county of Cook and State of Illinois, have invented certain new and useful Improvements in Automatic Valves, of which the following is a full, clear, and exact description, reference being had to the accompanying drawings, forming a part of this specification, in which—

10 Figure 1 is a vertical sectional view of said valve and the connecting parts as it appears when closed or in its normal condition. Fig. 2 is a like view showing said valve open; and Fig. 3 is a detail view in vertical section, showing a modification of said invention.

Like letters of reference in the different figures indicate like parts.

My invention relates more particularly to that class of valves which are employed to regulate the flow of water from the supply to the distributing-pipes in automatic fire extinguishing apparatus, such as is used in warehouses and factories, commonly known as the "dry-pipe" system; and my object is to so construct said valve that it may open automatically upon the escape of air from the distributing-pipes upon the opening of a sprinkler-head, while it is closed by the direct pressure of water against it and opened by means of the pressure of water from the service-pipe acting upon a piston of differential area and attached to the valve-rod.

To these ends my invention consists in the combination of elements hereinafter more particularly described and claimed.

Referring to the drawings, *a* represents that portion of the service or stand pipe connected with the source of water-supply, and which is normally filled with water, as indicated in Fig. 1, while *a'* is that part of said pipe which is connected with and becomes a part of the distributing-pipes, one of which is shown at *b*, Fig. 1. Between the parts *a* and *a'* of said service-pipe I interpose my improved valve *c*, which consists of a metal shell provided with interior compartments or partitions, which divide it into four chambers *d*, *e*, *f*, and *g*, which I term the "induction," "eduction," "piston," and "leak" chambers, respectively, the leak-chamber *g* being partially surrounded by the other three. The chamber *f* is of cy-

lindrical form and contains a piston *f'*, rigidly attached to a rod *h*, which is passed into or through the chambers *g* *d*, the opposite end being arranged to move in a suitable 55 guide, which may consist of a cross-bar, as shown at *j*, Fig. 1 or said rod may extend through a bore in a movable cap *d'*, Fig. 2, in which case the bearing is provided with the usual packing, as indicated at *d'* in said 60 last-named figure.

Upon the rod *h*, and located within the induction-chamber *d*, is a valve *k* of smaller superficial area than the piston *f'*, and which is adapted to be normally seated upon a valve-seat *k'*, which closes the inlet to the leak-chamber *g*, and normally prevents the water in the chamber *d* from entering it, said valve being held to its seat by the direct pressure of the water in the pipe *a*. Tapped into the 70 opening of the shell with which the pipe *a'* is connected is a "spider" *l*, which is bored to receive a valve-stem *m*, to which is attached a valve *m'*, the opposite end of the valve-stem passing loosely through a bore in a cross-bar 75 *n*, placed across the eduction-opening of the chamber *g*. Said valve is intended to rest normally upon a valve-seat *n'* at the mouth of said opening. A drain-pipe *o*, having a valve *o'*, is connected with the eduction-chamber *e*. A byway *p*, in which is interposed a puppet-valve *p'*, for normally closing said way, is arranged to connect the chambers *d* and *f*, the connection with latter being made between the piston *f'* and the piston-head 85 *f*², as clearly shown in the drawings, and the valve *p'* is arranged to close against the water-pressure in said byway. Above the valve-shell is located a chamber *q*, provided with a flexible diaphragm *q'*, to which is secured a weight *r*. A lever *r'* is loosely secured to said weight and pivoted to a rigid arm *r*², attached to the frame. A detent *r*³ upon the end of the lever serves to normally engage an arm *s*, which is pivoted to a stationary lug *s'*. A set-screw *s*², tapped through the arm *s*, rests normally against the stem of the valve *p'*, and enables the pressure upon said valve to be regulated to prevent leakage. An air-pump *t*, Fig. 1, is connected by means 95 of a pipe *t'* with the chamber *q*, and both the chamber *q* and the air-pump communicate 100

with the distributing-pipes *b* and the portion *a'* of the stand-pipe by means of a pipe *t*.

The distributing-pipes are provided with the usual automatic sprinklers, which are retained normally closed by means of fusible solder, one of which is shown at *b*, Fig. 1.

Upon placing the various parts in the respective positions (shown in Fig. 1) and pumping air into the distributing-pipes the dia-
phragm *q'* and weight *r* are raised, and the
detent *r* serves to hold the *S* in place. The
chamber *e* is filled with water up to the line
of the drain-pipe *o*, (see Fig. 1,) which serves
to prime the valve *m'*. The chamber *g* is
normally empty, and kept so by means of a
drain-pipe *u*, tapped into the bottom thereof, so
that any leakage of the valve *k* is drawn off
as fast as it occurs, thereby preventing its en-
trance to the distributing-pipes and chamber
q. Upon the opening of the sprinkler *b'* and
the consequent escape of air the weight *r*
falls, the lever *s* is released, the valve *p'*
opened, and the water permitted to flow into
the chamber *f* against the piston *f'*, which,
having a differential area, forces the valve *k*
open against the water-pressure in the cham-
ber *d*, lifts the valve *m'*, and passes to the
distributing-pipes.

In practice I prefer to interpose a water-
motor *v* in the drain-pipe *u*, and to connect
therewith a hammer *v'* and bell *v''*, so that
when the valve *k* is opened the water rushing
through the drain-pipe will serve to ring
an alarm. The common valve and piston-
rod *h* may be arranged horizontally, as in Fig.
1, or upon an incline, as shown in Fig. 2. In
the former case I prefer to have the valve ar-
ranged obliquely to the valve-stem. In the
latter it need not be.

It is obvious that the weight *r* and levers
connecting the same with the valve in the by-
way may be dispensed with and a diaphragm-
valve of differential area may be connected
with the distributing-pipes and with the valve
in said byway, so that the compressed air
may serve to act directly upon said valve.
Such a construction is shown in Fig. 3, in
which the diaphragm *q'* is inclosed within a
case and is connected with the valve-stem of
the valve *p'*, said diaphragm being arranged
to work in an opposite direction upon the
escape of air from the distributing-pipes from
that shown in Figs. 1 and 2.

Having thus described my invention, I
claim--

1. The combination, with the supply and
distributing pipes of a dry-pipe fire-extin-
guishing system, of a valve having an induc-
tion-chamber in direct communication with
the supply-pipe which is connected with a
source of water-supply, an adjacent leakage-
chamber normally empty having an opening
communicating with the atmosphere, the in-

duction-opening to said leak-chamber being
normally closed by a water-valve opening 65
against the water-pressure, an outlet from
said leak-chamber communicating with a
chamber connected with the distributing-pipe,
a valve for normally closing said outlet, a
piston-chamber and piston of differential area 70
connected with said valve in the induction-
chamber, a byway connecting said induction
and piston chambers, and means, as set forth,
for normally closing said byway-valve by the
pressure of air in the distributing-pipes, sub- 75
stantially as shown and described.

2. The combination, with the supply and
distributing pipes of an automatic fire-extin-
guishing system, of an automatic valve hav-
ing induction and eduction chambers, a nor-
mally-empty leak-chamber communicating 80
with said induction and eduction chambers,
valves for normally closing communication
between said leak-chamber and the induction
and eduction chambers, a piston-chamber, a 85
piston therein of larger area than the valve
in the induction-chamber and having its rod
connected with said valve, a byway connect-
ing the induction and piston chambers, a
valve for normally closing said byway against 90
the water-pressure, and means, as specified,
for releasing said valve upon the escape of
air from the distributing-pipes, substantially
as shown and described.

3. The combination, with the supply and 95
distributing pipes of a fire-extinguishing sys-
tem, the former being supplied with water
and the latter with air-pressure, of an auto-
matic valve provided with the chambers *d e*
f g, valves *k m'*, piston *f'*, byway *p*, valve *p'*, 100
a diaphragm-chamber in communication with
the distributing-pipes and a source of com-
pressed air, and a diaphragm therein in op-
erative connection with the valve in said by-
way, substantially as shown and described. 105

4. The combination, with the supply and
distributing pipes of a fire-extinguishing sys-
tem, the former being supplied with water
and the latter with air under pressure, of an
automatic valve provided with the chambers 110
d e f g, valves *k m'*, piston *f'*, byway *p*, valve
p', a diaphragm-chamber in communication
with the distributing-pipes and a source of
compressed air, and a diaphragm therein in
operative connection with the valve in said 115
byway, drip-pipe *u*, having a water-motor in-
terposed therein in operative connection with
an alarm-bell, substantially as shown and de-
scribed.

In testimony whereof I have signed this 120
specification, in the presence of two subscrib-
ing witnesses, this 16th day of October, 1889.

JOSEPH CLAPP.
